US00D914719S

(12) **United States Design Patent** (10) Patent No.: **US D914,719 S**
 Ryan et al. (45) Date of Patent: ** *Mar. 30, 2021

(54) **DISPLAY SCREEN OR PORTION THEREOF WITH GRAPHICAL USER INTERFACE**

(71) Applicant: **CARNAHAN GROUP, INC.**, Tampa, FL (US)

(72) Inventors: **Meghan Ryan**, Tampa, FL (US); **Christopher T Carnahan**, Tampa, FL (US); **Michael Kuck**, Tampa, FL (US)

(73) Assignee: **Carnahan Group, Inc.**, Tampa, FL (US)

(*) Notice: This patent is subject to a terminal disclaimer.

(**) Term: **15 Years**

(21) Appl. No.: **29/690,987**

(22) Filed: **May 13, 2019**

Horizontal stacked bar chart with only two alternating conditions, ergo colors, by Vathek, dated Jun. 19, 2012, social.technet.microsoft.com [online]. Retrieved Sep. 23, 2020 from internet. (Year: 2012).*

Primary Examiner — Andrew T Nemeth

(57) **CLAIM**

The ornamental design for a display screen or portion thereof with graphical user interface, as shown and described.

DESCRIPTION

FIG. 1 is a front view of a display screen or portion thereof with graphical user interface, showing our new design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; and, FIG. 6 is a front view of a sixth embodiment thereof. The outermost broken lines in the figures show a display screen or portion thereof. The remaining broken lines illustrate portions of the graphical user interface. None of the broken lines form part of the claimed design.

1 Claim, 4 Drawing Sheets
